UNITED STATES PATENT OFFICE.

CHARLES B. BIRD, OF SIOUX CITY, IOWA, ASSIGNOR TO ELLEN O. BIRD,
OF SAME PLACE.

SUSPENDER-BUCKLE.

SPECIFICATION forming part of Letters Patent No. 340,089, dated April 20, 1886.

Application filed October 16, 1885. Serial No. 180,073. (No model.)

To all whom it may concern.

Be it known that I, CHARLES B. BIRD, a citizen of the United States, residing at Sioux City, in the county of Woodbury, State of Iowa, have invented certain new and useful Improvements in Suspender-Buckles; and I hereby declare the following to be a full, clear, and exact description of the same.

My invention relates to buckles for securing 15 the end to the strap of suspenders, and more particularly to the class in which means are provided whereby the reach may be separated from the strap without removing the buckle from the latter; and the object of my invention 15 is to provide a buckle of this nature simple in construction, with the smallest possible number of parts, and in such a way that the parts may be made readily and at a minimum cost.

To this end my invention consists in a buckle 20 comprising a slide for the strap and a clamp for the purpose of retaining the strap in its adjustment in the slide, which shall constitute at the same time a connection between the buckle and the reach and a cast-off whereby 25 the reach may be detached from the buckle.

Referring to the drawings, Figure 1 is an elevation of my device in its approved form, and Figs. 2 and 3 details.

A is the slide, made of a single strip of metal, 30 bent as shown. This slide has a part cut away, the sides being converging, as shown at t, and is further provided with the transverse recesses s s', forming extensions of the cut-away part t and leaving the shoulder r. A convenient way to construct the slide is to stamp the metal strip before bending, so as to leave at 35 each end the configuration necessary to form the cut-away t, recesses s s', and shoulder r, when the strip is bent over to cause the ends 40 to meet and form a slide.

B is the clamp or bearing-tongue, which constitutes at the same time a connector and a cast-off. The clamp comprises the plate p and head o, and is provided with recesses n at 45 the junction of the extension and plate. The plate is provided with means of attaching the reach to it, which means may consist in the slots arranged in the outline of a triangle, as shown, or any other form. The head o is bent 50 to project at about a right angle from the plate, to constitute the bearing end of the

clamp, and may or may not be provided with a serrated bearing-edge. The width of the plate between the inner ends of the recesses n is greater than the width of the cut-away part 55 of the slide between the shoulders r, and less than the cut-away part between the inner ends of the recesses s s', the latter being less in width than the head o.

As thus constructed, the operation of the device is as follows: The plate B, having the reach attached, is inserted into the recess s in an oblique direction, as shown in Fig. 2, the head o being within the slide. The width of the plate between the recesses n being very 60 little greater than the width of the cut-away between the shoulders r, the projection of the plate into the recess s permits its passage between the shoulders into the position shown in full lines in Fig. 1. By this construction 65 the clamp is capable of a movement, as on a fixed pivot, in the recesses s s', as will readily be seen.

To remove the clamp it is necessary to lift the free end of the bearing-tongue to a position substantially at a right angle with the slide, push the plate farther into one of the slots, s or s', and raise the opposite end of the plate into the oblique position shown in dotted lines in Fig. 1. The width of the head o being 70 greater than the width between the recesses 75 s s', the removal of the clamp, except in the manner described, is impossible.

A device thus constructed provides all the essentials to a buckle of the character named, 80 while employing but two parts, each of which is capable of being made at a minimum cost. I do not, however, limit myself to the specific construction shown, as various modifications may readily be conceived, the broad feature 85 of my invention being the construction of a buckle having a clamp detachably connected therewith, thereby accomplishing the triple purpose of a clamp, connector, and cast-off.

What I claim as new, and desire to claim 90 by Letters Patent, is—

1. The suspender-buckle, substantially as herein shown and described, comprising a slide and a clamp detachably pivoted in the slide, as set forth.

2. A buckle comprising a slide having a 95 cut-away part, t s s', and a clamp detachably

inserted into the cut-away part of the slide, substantially as described.

3. A buckle comprising the following elements: a slide having the cut-away part $t s s'$, and a clamp comprising the plate p and head o , bent at right angles to the plate, said plate being provided with the recesses n , whereby the said clamp is detachably adjustable to the slide, as set forth.

4. The suspender-buckle, substantially as to herein shown and described, comprising a slide and a clamp detachably pivoted in the slide and provided with means for attaching the suspender-end thereto, as set forth.

CHAS. B. BIRD.

In presence of—

WALTER R. RHOTON,
S. D. BLYTHE.
